CLAIM

The ornamental design for a book holder, as shown and described.

DESCRIPTION

FIG. 1 is a rear perspective view of a book holder showing my new design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a front elevational view thereof; and

FIG. 7 is a rear elevational view thereof.

FIGS. 2-7 have been drawn at a reduced scale for convenience of illustration.
